UNITED STATES PATENT OFFICE.

WINFIELD S. ANDERSON, OF CINCINNATI, OHIO.

CUPOLA.

No. 820,167.

Specification of Letters Patent.

Patented May 8, 1906.

Application filed August 28, 1905. Serial No. 276,034.

To all whom it may concern:

Be it known that I, WINFIELD S. ANDERSON, a citizen of the United States, residing at Cincinnati, Hamilton county, State of Ohio, have invented certain new and useful Improvements in Cupolas; and I do declare the following to be a clear, full, and exact description of the invention, attention being called to the accompanying drawings, with the reference characters marked thereon, which form also a part of this specification.

This invention relates to improvements in devices for smelting and reducing ore or for melting metal, as is done in blast-furnaces, cupolas, &c.; and it relates more particularly to such where a vaporized liquid fuel or hydrocarbon—like crude oil, for instance—is used as fuel.

The invention embraces features relating to the general construction, means for vaporizing the hydrocarbon, and devices for regulating the supply of the same. These features of my invention are arranged and constructed in a manner to permit their installation and provision in connection with existing furnaces without requiring extensive alterations or disturbance of prevailing arrangements.

In the following specification and claims at the end thereof is found a full description of my invention, together with its parts, their operation and construction, which latter is also illustrated in the accompanying drawings, which show my invention in connection with a customary cupola, and in which drawings—

Figure 1 shows the lower part of such a cupola, partly in elevation and partly in section and provided with the improvements contemplated by my invention. Fig. 2 is part of a horizontal section of Fig. 1. Fig. 3 is a detail view of the means for regulating the air-blast passing through the twyters.

In the drawings, 10 indicates the general wall of the structure, the same forming an inclosure which receives the charge (ore or metal) through a charging-door 11 to be reduced or melted in the lower part or working chamber 12 of the inclosed space where such charge comes in contact with heat and fuel. In cupolas this wall usually rests upon a sub-structure consisting of a base 13 and pillars 14. The molten metal is drawn off through a customary tap-hole. (Not shown.) Air is blown into the working chamber through twyters 15, provided in the inclosing wall 10, and whereby the melting effects of the combustion are intensified. The air for this blast is supplied in any suitable way. Usually an annular chamber 16 is provided to surround wall 10 outside of the working chamber, the inclosed space being customarily known as the "wind-box" and with which space the outer ends of all the twyters are in open communication, so that the air from this box may simultaneously pass through all twyter-openings. The wind-box is supplied through a pipe 17 from a suitable source, like a blower or air-compressor.

As before stated, the fuel is presumed to be a hydrocarbon—like crude oil, for instance—which is supplied by burner-pipes 18 and discharges through burner-nozzles 19 into working chamber 12. These burner-nozzles enter this latter through the twyters, so that an existing coal or coke burning structure may be readily converted into an oil-burning one and provided with the necessary outfit for this purpose without requiring cutting of holes to admit the burner-nozzles, since these latter may enter through the existing twyters. The burner-pipes are supplied from feed-pipes 20, which supply is controlled by suitable valves 21. These feed-pipes are all in communication with and start from a vaporizing-pipe 22, which lies closely around the outside of the furnace-wall, so as to be heated thereby, and whereby the oil contained in it is also heated and converted more or less into vapor. This conversion may be aided by providing heaters in form of short pipe-spurs 23, capped at their outer end, but open to pipe 22, and embedded in the furnace-wall, where a higher degree of heat prevails. They may also constitute the means to hold pipe 22 in position. A general supply-pipe 24, controlled by a valve 25, brings the oil to the furnace, the flow being induced by pump or gravity. A gage 26 indicates the pressure within the generating-pipe 22, and to guard against accidents I provide a weight or spring controlled safety-valve 27, any blow-off being received by a pipe 28, whereby it is returned to the general supply. The air passing through twyters 15 may be controlled and regulated, for which purpose I provide curtain-valves 29, one being above each opening and each connected to a rod 31, which is supported in the furnace-wall and in the outer wall of the air-chamber and provided outside of this latter with a handle 32 for manipulation, which is by adjusting it across a twyter-

opening, as best shown in Fig. 3. The burner-pipes 18 are bent accordingly to permit said valves 29 to close the larger part of a twyer-opening; but within said opening each pipe is 5 bent toward the center again, so as to cause the oil and vapor to discharge centrally from the twyer-openings.

The escape of the heat is retarded by an 10 annular check 33 to concentrate its action 15 and to intensify its effect on the matter to be reduced.

Having described my invention, I claim as new—

1. In a cupola or similar device fitted for 15 using liquid fuel, the combination of a working chamber, a fuel-heating pipe arranged around the wall which surrounds this working chamber and provided with communicating, inwardly-projecting heating-spurs which 20 are embedded into this wall so as to derive heat therefrom, means to supply a hydrocarbon to this pipe and its spurs so as to be pre-heated therein, burner-nozzles arranged to

discharge into the working chamber and feed-pipes connecting them with the fuel-heating 25 pipe.

2. In a cupola or similar device fitted for 30 using liquid fuel, the combination of a working chamber, a fuel-heating pipe around the outside of the same which has inwardly-projecting, communicating pipe-spurs which are embedded in the adjacent chamber-wall for the purpose of supporting the fuel-heating pipe which surrounds this wall so as to derive heat therefrom, means to convey a hydrocarbon 35 to this heating-pipe to be preheated therein, burner-nozzles arranged to discharge into the working chamber and feed-pipes connecting them with the fuel-heating pipe.

In testimony whereof I hereunto affix my 40 signature in the presence of two witnesses.

WINFIELD S. ANDERSON.
